(57) **CLAIM**

The ornamental design for a case for electronic devices, as shown and described.

DESCRIPTION

FIG. 1 is a front perspective view of a case for electronic devices showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front exploded perspective view thereof;

FIG. 10 is a rear exploded perspective view thereof;

FIG. 11 is a front perspective view of the inner shell of the case, shown isolated from the case for electronic devices for clarity;

FIG. 12 is a rear perspective view of the inner shell of the case, shown isolated from the case for electronic devices for clarity;

FIG. 13 is a front perspective view of the outer frame of the case, shown isolated from the case for electronic devices for clarity; and,

FIG. 14 is a rear perspective view of the outer frame of the case, shown isolated from the case for electronic devices for clarity.

Although the case for electronic devices in which the claimed design is embodied consists of an inner shell and an outer frame, the claim is directed to the ornamental appearance of the case for electronic devices in its entirety and does not extend to the ornamental appearance of each of the individual components in isolation.

The broken lines depict portions of the case for electronic devices that form no part of the claimed design. The broken lines and regions bounded by broken lines form no part of the claimed design.
